(57) **CLAIM**

We claim the ornamental design for a mounting arm, as shown and described.

DESCRIPTION

FIG. 1 is a front perspective view of a mounting arm in accordance with our new design;

FIG. 2 is a rear perspective view of the mounting arm of FIG. 1;

FIG. 3 is a front elevation view of the mounting arm of FIG. 1;

FIG. 4 is a rear elevation view of the mounting arm of FIG. 1;

FIG. 5 is a right-side elevation view of the mounting arm of FIG. 1;

FIG. 6 is a left-side elevation view of the mounting arm of FIG. 1;

FIG. 7 is a top plan view of the mounting arm of FIG. 1; and,

FIG. 8 is a bottom plan view of the mounting arm of FIG. 1.

(Continued)

The broken lines depict portions of the mounting arm that form no part of the claimed design.
